United States Patent

Des. 239,905
Patented May 18, 1976

239,905

DISPLAY STAND

Samuel Grimaldo, 776 W. Sandoval,
Thousand Oaks, Calif. 91360

Filed May 27, 1975, Ser. No. 580,957

Term of patent 14 years

Int. Cl. D6—04; D20—02

U.S. Cl. D6—24

FIG. 1 is a side elevational view of a display stand showing my new design;

FIG. 2 is a front perspective view thereof;

FIG. 3 is a side elevational view thereof, opposite to the side shown in FIG. 1;

FIG. 4 is a top plan view thereof;

FIG. 5 is a bottom plan view thereof;

FIG. 6 is a rear perspective view thereof; and

FIG. 7 is a cross sectional view taken through lines 7—7 of FIG. 6.

I claim:

The ornamental design for a display stand, substantially as shown.
